LADDER

Provance H. Buttermore, Painesville, Ohio, and
Robert S. Field, Palm Springs, Calif.

Application December 14, 1956, Serial No. 628,261

1 Claim. (Cl. 228—36)

The present invention relates to new and useful improvements in straight ladders and has for its primary object to provide, in a manner as hereinafter set forth, a ladder of this type which may be expeditiously folded or collapsed for storage or transport.

Another very important object of the invention is to provide a ladder of the aforementioned character comprising an extension which may be readily brought into use if needed.

Still another important object of the invention is to provide, in a collapsible straight ladder and an extension therefor, novel means for removably but firmly securing the extension in position on the ladder.

Other objects of the invention are to provide a ladder of the character set forth which will be comparatively simple in construction, strong, durable, compact, of light weight and which may be manufactured at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in front elevation of a ladder constructed in accordance with the present invention;

Figure 2 is a front elevational view, showing the ladder folded or collapsed;

Figure 3 is an enlarged view in horizontal section, taken substantially on the line 3—3 of Figure 1;

Figure 4 is an enlarged fragmentary view in transverse section, taken substantially on the line 4—4 of Figure 1;

Figure 5 is a fragmentary view in vertical section, taken substantially on the line 5—5 of Figure 4; and

Figure 6 is an enlarged view in front elevation and partially in vertical section, showing an extension mounted on the ladder.

Referring now to the drawing in detail, it will be seen that the embodiment of the invention which has been illustrated comprises a pair of side rails of magnesium, aluminum or other suitable material which are designated generally by reference character 7. The rails 7, which may also be of any desired dimensions, are in the form of opposed channel bars, said side rails including webs 8 and flanges 9. Braces 10 are provided between the opposed flanges 9 at suitably spaced points in the rails 7. The upper ends of the flanges 9 have formed therein notches or recesses 11.

Also mounted between the opposed flanges 9 at longitudinally spaced points on the rails 7 are headed metallic pins or shafts 12. Tubular rungs 13 have their end portions journaled on the shafts 12. Spacers 14 are mounted on the shafts 12 between the rungs 13 and flanges 9. Thrust bearings 15 in the form of washers are mounted on the shafts 12 between the spacers 14 and

2

the rungs 13. The rungs 13 pivotally connect the rails 7 for swinging movement in parallelism.

The upper end portions of the rails 7 have formed in the webs 8 thereof circular openings 16 (see Figure 6) for the reception of the end portions of a removable tubular rung 17. The projecting end portions of the rung 17 are apertured for the reception of cotter pins 18 for securing said rung 17 in position on the rails 7. The removable rung 17 secures the rails 7 in open position against swinging movement.

The members 7, 13, 17, etc., provide a straight ladder which is designated generally by reference character 19. Removably mounted on the upper end portion of the ladder 19 is an extension 20. The extension 20 includes a pair of substantially channel-shaped side rails 21 the lower end portions of which are slidably insertable downwardly in the upper end portions of the ladder rails 7. Circular openings in the webs of the rails 21 accommodate the removable rung 17 of the ladder 19. Tubular rungs 22, substantially similar to the rungs 13, have their end portions journaled on headed pins or shafts 23 which are mounted between the flanges of the rails 21. The pins or shafts 23 and 12 are also substantially similar. The lower ends of the flanges of the rails 21 have formed therein notches or recesses 24 for the reception of the uppermost pins or shafts 12 of the ladder 19. The heads 25 of the pins or shafts 23 are engageable in the notches or recesses 11 in the upper ends of the ladder rails 7.

It is thought that the invention will be readily understood from a consideration of the foregoing. Briefly, with the removable rung 17 in position in the upper end portion of the ladder 19, said ladder is positively secured in open position for use. By removing the rung 17 the ladder 19 may be readily folded or collapsed to the position of Figure 2 of the drawing with the opposed side rails 7 in abutting engagement with each other. To use the extension 20, the ladder 19 is opened and the lower end portions of the rails 21 are engaged in the upper end portions of the rails 7, the notches or recesses 24 receiving the uppermost shafts 12, the heads 25 of the shafts 23 engaging in the notches or recesses 11 in the upper ends of the flanges 9. The rung 17 is then inserted through the rails 7 and 21 and the cotter pins 18 are inserted in the end portions of said rung for securing the assembly. Of course, to remove the extension 20 the foregoing procedure is substantially reversed. If desired, suitable removable shoes or boots may be provided on the lower end portions of the rails 7.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

A collapsible ladder comprising: a pair of opposed, substantially channel-shaped side rails, said side rails including a web and opposed flanges integral with said web, said flanges having notches in one end thereof, shafts extending between the flanges of the rails, tubular rungs having their end portions journaled on said shafts and spaced from said webs for pivotally connecting the side rails for swinging of said rungs on said shafts in opposite directions to fold the ladder, and a collapsible extension removably mounted on the ladder, said extension comprising substantially channel-shaped side rails engageable in certain end portions of the ladder rails, shafts mounted between the flanges of the extension rails, cer-

tain of the second named shafts including heads on their ends engageable in the notches of the ladder, tubular rungs having their end portions journaled on the second named shafts for pivotally connecting the extension rails, said extension rails having notches in the lower end portions thereof for the reception of the uppermost of the first named shafts, and means for positively connecting the extension to the ladder, said ladder and extension rails having aligned openings therein, said means comprising a removable rung having its end portions fixed in the openings.
